(57) **CLAIM**

The ornamental design for a skin mesher, as shown and described.

DESCRIPTION

FIG. 1 is a perspective view showing the skin mesher;
 FIG. 2 is a front elevation view thereof;
 FIG. 3 is a rear elevation view thereof;
 FIG. 4 is a right side elevation view thereof;
 FIG. 5 is a left side elevation view thereof;
 FIG. 6 is a top plan view thereof;
 FIG. 7 is a bottom plan view thereof; and,
 FIG. 8 is a perspective view showing an alternate position of the skin mesher.
 The broken lines shown in FIGS. 1-8 illustrate portions of the skin mesher that form no part of the claimed design.
